UNITED STATES PATENT OFFICE.

ALBERT E. HOLADAY, OF NAUGATUCK, CONNECTICUT, ASSIGNOR TO JOHN FRANCIS HEMENWAY, OF NEW YORK, N. Y.

PRESSURE-RELEASE FOR CLOTHES-WRINGERS.

1,284,105.

Specification of Letters Patent.

Patented Nov. 5, 1918.

Application filed January 18, 1917. Serial No. 143,090.

To all whom it may concern:

Be it known that I, ALBERT E. HOLADAY, a citizen of the United States, residing at Naugatuck, in the county of New Haven and 5 State of Connecticut, have invented certain new and useful Improvements in Pressure-Releases for Clothes-Wringers, of which the following is a specification, reference being had therein to the accompanying drawing.

10 This invention relates to certain new and useful improvements in clothes wringers, and more particularly to a pressure release for the same, the object being to provide a clothes wringer with an invisible pressure release so constructed that the same will be automatically operated by the abnormal separation of the rolls, means being provided for manually operating the same in case of the failure of the automatic means working. 15 Another object of my invention is to provide a release which is exceedingly simple and cheap in construction and one which can be readily applied to the various forms of wringers now in use, the releasing members being mounted within the coil pressure springs in such a manner that they are raised 20 vertically on the abnormal separation of the rolls and brought into engagement with pivoted latches carried by the top bar so as to move the latches out of engagement with the keepers carried by the frame of the wringer in order to release the pressure. 25

Another and further object of the invention is to provide a novel form of manually 30 operated means for operating the latches through the medium of a push button mounted in the top bar.

Other and further objects and advantages 35 of the invention will be hereinafter set forth and the novel features thereof defined by the appended claims.

In the drawings,

40 Figure 1 is a side elevation partly in section showing the application of my improved construction of release, the top bar being shown raised in dotted lines;

Fig. 2 is a perspective view of the parts of the release detached;

45 Fig. 3 is a detail enlarged section showing the relative position of the manually operated members and automatically operated members in respect to the latches employed for holding the top bar in predetermined position;

50 Fig. 4 is a detail view of one of the latches

showing the manner of mounting the same in the angled plate carried by the top bar;

Fig. 5 is a detail section showing a slightly modified form of bearing and releasing bar.

Like numerals of reference refer to like 60 parts in the several figures of the drawing.

In carrying out my invention I employ a wringer frame 1 having slotted side bars 2 in which are mounted pressure roll carrying shafts 3 and 4, provided with the usual pressure rolls 5 and 6, said rolls carrying meshing gears, not shown, inclosed by gear casings 7. The lower pressure roll carrying shaft 3 is mounted in fixed bearings 8 and mounted on the upper pressure roll carrying 65 shaft 4 are bearings 9 carrying pressure springs 10 which are engaged by bearing plates 11 carried by the ends of the pressure bar 12, said bearing plates being provided with apertured lugs 13 extending down into 70 the convolutions of the pressure springs 10 as clearly shown in Figs. 1 and 3.

Secured across the slots of the side bars 2 at their upper ends are keepers 14 in the form of plates having openings 15, the lower 80 edges of which are beveled as shown at 16 for the purpose hereinafter fully described.

Arranged within the slotted side bars between the keepers is a movably mounted top bar 17 which is provided with recesses 18 at its ends over which are arranged angled plates 19 provided with spaced apertured ears 20 in which are mounted latches 21 upon pivots 22 extending through the apertures of the ears 20 as clearly shown in Fig. 4, 90 said latches being provided with tail portions 23 having positioning pins 24 over which are arranged coil springs 25^a which are held in position on the angled plates by positioning pins so as to normally hold the 95 pivoted latches in extended position under the lower edges of the keepers 15 in order to hold the top bar in predetermined position.

The top bar is provided with pressure screws 25 which engage the bearing plates 100 11 of the pressure bar 12 so as to adjust the pressure on the pressure rolls 5 and 6 in the ordinary manner.

In order to provide means for manually operating the pivoted latches 21 I provide 105 the top bar with a centrally disposed vertical bore 26 which communicates with the longitudinal slots 27 formed in the under side of the top bar as clearly shown in Fig. 1. Pivots mounted within the slots 27 are 115

levers 28 which are provided with angled ends 29 adapted to engage the beveled faces of lugs 30 formed on the tail portions 23 of the latches 22 so as to rock said latches on 5 their pivots in order to move the latches out of engagement with the keepers which allows the top bar to move vertically within the frame, and as the latches move upwardly they ride into the openings 15 of the keepers 10 so as to prevent the top bar from jumping out of the frame. Slidably mounted within the bore 26 is a push button 31 which is provided with a cross pin 32 at its lower end on which the inner ends of the levers 22 are 15 mounted, said push button having a slot 33 through which passes a pin 34 for holding the push button in position within the top bar, and it will be seen that when the push button is forced downwardly the levers are 20 rocked on their pivots so as to oscillate the pivoted latches in order to release the top bar.

In connection with the manually operated means for operating the pivoted latches 22 I provide automatic means comprising releasing bars 35 arranged within the coil pressure springs 10, the lower ends of said bars extending through the apertured bosses 9' of the bearing 9 and rest upon the upper pressure roll carrying shaft 4 as clearly 25 shown in Fig. 1. The upper end portions of the releasing bars 35 extend through the apertured bosses 13 of the bearing plates 11, and are provided with internally threaded bores in which are adjustably mounted trip 30 members 36 herein shown in the form of screws which can be rotated so as to adjust the relative position of the heads thereof in respect to the latches. As the pressure rolls 5 and 6 are separated abnormally the releasing 35 bars 35 are moved upwardly so as to throw the trip members 36 into engagement with the tail portions of the latches which rocks the latches so as to move the latches out of engagement with the keepers and allows 40 the top bar to move a predetermined distance upwardly within the frame to release the pressure rolls.

In the modification shown in Fig. 5 I provide a bearing 37 with a socket 38 in which 50 the lower end of a releasing bar 39 is secured by a pin 40 so as to connect the releasing rod to the bearing in order to prevent the same from turning to facilitate the adjusting of the trip members and to prevent the wearing 55 of the releasing rod, or the danger of the same jumping out of the bearing when the pressure is released.

In the operation of a clothes wringer as herein shown and described assuming that 60 the parts are in the position as shown in Fig. 1 when a thick bunch of clothes or an operator's hand is drawn between the pressure rolls so as to separate the rolls abnormally, the releasing bars are moved upwardly so as 65 to throw the trip members into engagement

with the latches which moves the latches out of engagement with the keepers and the top bar moves vertically within the frame until the latches ride into the openings of the keepers which prevents the top bar from jumping out of the frame.

In case of the automatic means failing to work so as to release the pressure on the pressure rolls, the push button can be struck by the operator so as to throw the levers into 75 engagement with the latches which moves the latches out of engagement with the keepers and allows the top bar to move vertically to release the pressure. After the pressure has been released and it is desired to reset 80 the device, the pressure screws are adjusted so as to move the screws upwardly and by striking the top bar the latches ride on the inclined edges of the openings of the keepers back into position under the lower edges 85 thereof to enable the pressure screws to be again adjusted so as to obtain the desired pressure on the pressure rolls.

From the foregoing description it will be seen that I have provided a pressure release 90 for a clothes wringer in which a pair of pivotally mounted latches are mounted within the top bar in such position that they can be engaged by automatically operated releasing members or manually operated releasing 95 members so as to move the latches out of engagement with the keepers carried by the frame to release the top bar.

While I have shown and described the releasing bars arranged within sockets formed 100 in the upper bearings in a particular manner, I do not wish to limit myself to any particular manner of mounting these releasing bars in the bearings as any suitable means can be employed for mounting the rods in 105 the bearings without departing from the spirit of my invention.

I claim—

1. A clothes wringer, comprising a frame having pressure rolls and pressure means for 110 said rolls mounted therein, including coiled pressure springs, a top bar movably mounted in said frame having means for adjusting said pressure springs, pivoted members carried by said top bar for holding the same in 115 predetermined position within said frame, and releasing bars arranged within the pressure springs actuated by the movement of the upper roll and adapted to engage said latches on the abnormal separation of said 120 rolls for moving said latches in position to release said top bar.

2. A clothes wringer, comprising a frame having a pair of superposed pressure rolls mounted therein, one of said rolls being 125 movably mounted in respect to the other roll, bearings mounted on the shaft of the upper roll, pressure springs mounted upon said bearings, releasing bars carried by said bearings arranged within said springs actu- 130

ated by the movable roll, a top bar movably mounted in said frame, pivoted latches carried by said top bar for holding said top bar in predetermined position within said frame, said releasing bars carrying adjustable trip members adapted to engage said latches on the abnormal separation of said rolls for moving said latches in position to release said top bar.

10 3. A clothes wringer, comprising a pair of superposed pressure rolls mounted therein provided with shafts, bearings mounted on the shaft of the upper pressure roll, releasing bars mounted in said bearings, coil springs mounted on said bearings surrounding said releasing bars, a top bar movably mounted in said frame having means for adjusting said pressure springs, means carried by said top bar for holding said top bar in predetermined position within said frame, said releasing bars engaging said retaining means on the abnormal separation of said rolls for releasing said top bar.

4. A clothes wringer, comprising a frame having a pair of superposed pressure rolls mounted therein, one of said rolls being movably mounted in respect to the other roll, each of said rolls being provided with a shaft, bearings mounted upon the shaft of the upper pressure roll, pressure springs mounted upon said bearings, a top bar movably mounted within said frame having means for adjusting said pressure means, keepers carried by said frame, pivoted latches mounted in said top bar engaging said keepers for holding said top bar in predetermined position within said frame, and releasing bars carried by said bearings arranged within the pressure springs having trip members engaging said latches on the abnormal separation of said rolls for moving said latches out of engagement with said keepers for allowing said top bar to move vertically within said frame.

45 5. A clothes wringer, comprising a frame having pressure rolls and pressure means for said rolls mounted therein, a top bar movably mounted in said frame having means for adjusting said pressure means, said top bar having recessed ends, plates arranged over said ends carrying pivoted latches having tail portions, keepers carried by the side bars of said frame adapted to be engaged by said latches for holding said top bar in predetermined position within said frame, and releasing bars actuated by said pressure roll and arranged to engage the tail portions of said latches on the abnormal separation of said rolls for releasing said pressure means.

60 6. A clothes wringer, comprising a frame having pressure rolls and pressure means for said rolls mounted therein, a top bar movably mounted in said frame having means for adjusting said pressure means, said top bar having recessed ends, angled

plates secured over the ends of said top bar carrying pivoted latches having tail portions, keepers carried by the side bars of said frame adapted to be engaged by said latches, said top bar having longitudinal slots, levers mounted in said slots having angled ends extending into the recesses of said top bar under the tail portions of said latches, and a push button mounted in said top bar having a connection with the inner ends of said levers for moving said levers into engagement with said latches for moving said latches in position to release said top bar.

70 7. A clothes wringer, comprising a frame having slotted side bars, superposed pressure rolls mounted in said frame having shafts extending into the slots of said side bars, bearings carried by the shaft of the upper pressure roll, pressure springs mounted on said bearings, a pressure bar carrying apertured bearing plates mounted on said pressure springs, a top bar movably mounted in said frame having means engaging said bearing plates for adjusting said pressure springs, means carried by said top bar for holding said top bar in predetermined position within said frame, and releasing bars mounted upon the bearings of the upper pressure roll shaft within the pressure springs adapted to engage said retaining means on the abnormal separation of said rolls for releasing said top bar.

8. A clothes wringer, comprising a frame having a pair of superposed pressure rolls mounted therein provided with shafts, bearings mounted on the shaft of the upper pressure roll, pressure springs mounted upon said bearings, a pressure bar carrying apertured bearing plates mounted upon said pressure springs, a top bar movably mounted in said frame having means for holding said top bar in predetermined position therein, releasing bars mounted on the bearings of the upper pressure roll shaft extending through the bearings of the pressure bar, and cooperating with the retaining means of said top bar on the abnormal separation of said rolls for releasing said top bar.

115 9. A clothes wringer, comprising a frame having slotted side bars, bearings fixed in the slots of said side bars, a pressure roll carrying shaft mounted in said bearings, a movable pressure roll carrying shaft mounted in said frame extending into the slots of the side bars thereof, bearings mounted on the shaft of the movable pressure roll provided with spring supports, springs mounted upon said supports, a pressure bar mounted upon said springs, a movably mounted top bar arranged within said frame having means engaging said pressure bar for adjusting the pressure on said roll, said top bar carrying pivoted latches, keepers

carried by the side bar adapted to be engaged by said latches, and releasing bars carried by the bearings of the upper pressure roll shaft having adjustable trip members arranged to engage said latches on the abnormal separation of said rolls for releasing said pressure means.

10. A clothes wringer, comprising a frame having a pair of superposed pressure rolls mounted therein provided with shafts, bearings mounted on the shaft of the upper pressure roll, coiled pressure springs mounted upon said bearings, apertured bearing plates mounted upon said pressure springs, 15 a pressure bar connecting said bearing plates, a top bar movably mounted in said frame having means engaging said bearing plates for adjusting said pressure springs, keepers carried by the side bars of said 20 frame, pivoted latches mounted in the ends of said top bar engaging said keepers, said latches having tail portions, and releasing bars carried by the bearings of the upper pressure roll shaft within the pressure 25 springs and extending through the bearing plates of the pressure bar having adjustable trip members adapted to engage the tail portions of said latches on the abnormal separation of said rolls for moving said latches 30 out of engagement with said keepers to allow said top bar to move vertically within said frame.

11. A clothes wringer, comprising a frame having pressure rolls and pressure means 35 for said rolls mounted therein, a top bar movably mounted in said frame having means for adjusting said pressure means, keepers secured to the side bars, pivoted latches mounted in the ends of said top bar 40 adapted to engage said keepers for holding said top bar in predetermined position within said frame, releasing members operated by the abnormal separation of said rolls engaging said latches for moving said 45 latches out of engagement with said keepers

to release said top bar, said keepers having openings adapted to receive the latches of said top bar on the upward movement thereof.

12. A clothes wringer, comprising a frame 50 having pressure rolls and pressure means for said rolls mounted therein, including coil pressure springs and a pressure bar, a top bar movably mounted in said frame having means for adjusting said pressure 55 springs, spring actuated latches carried by said top bar for holding said top bar in predetermined position within said frame, and releasing bars arranged within the pressure springs and operated by the abnormal 60 separation of said rolls for moving said latches in position to release said top bar.

13. A clothes wringer, comprising a frame having a pair of superposed pressure rolls mounted therein provided with shafts, bearings mounted on the shaft of the upper pressure rolls, coil pressure springs mounted upon said bearings, a top bar movably mounted in said frame having means for adjusting said pressure springs, keepers carried by the side bars of said frame, spring actuated latches carried by said top bar engaging said keepers having tail portions, releasing bars mounted in the bearings of the upper pressure roll carrying shaft with- 75 in the pressure springs, said releasing bars being provided with threaded bores, and trip members working in the threaded bores of said releasing bars adapted to engage the tail portions of said latches on the abnormal 80 separation of said pressure rolls for moving said latches in position to release said top bar.

In testimony whereof I hereunto affix my signature in the presence of two witnesses. 85

ALBERT E. HOLADAY.
